INFANT'S CONVERTIBLE CAR SEAT

Earl F. Hamilton, Columbus, Ind., assignor to Hamilton Cosco, Inc., Columbus, Ind., a corporation of Indiana

Filed Nov. 30, 1959, Ser. No. 58,521

Term of patent 14 years

(Cl. D15—1)

Fig. 1.

Fig. 2.

Fig. 3

Fig. 1 is a perspective view of an infant's convertible car seat, showing my new design, and showing the same in its car seat-forming position;

Fig. 2 is a perspective view of the infant's convertible car seat shown in Fig. 1, but showing the same in its crib-forming position; and

Fig. 3 is a rear perspective view of the infant's convertible car seat shown in Fig. 1.

The dominant features of the design reside in the portion shown in full lines.

I claim:

The ornamental design for an infant's convertible car seat, as shown and described.
